UNITED STATES PATENT OFFICE

RICHARD WHITAKER, OF NEW BRUNSWICK, NEW JERSEY, ASSIGNOR TO
THE NEVERSLIP MANUFACTURING COMPANY, OF NEW BRUNSWICK,
NEW JERSEY.

DESIGN FOR A HORSESHOE-CALK.

SPECIFICATION forming part of Design No. 35,330, dated November 26, 1901.

Application filed October 27, 1900. Serial No. 34,672. Term of patent 14 years.

To all whom it may concern:

Be it known that I, RICHARD WHITAKER, a citizen of the United States, residing at New Brunswick, in the county of Middlesex and State of New Jersey, have invented and produced a new and original Design for a Horseshoe-Calk; and I do hereby declare the following to be a full, clear, and exact description of the same, reference being had to the accompanying drawings, forming a part thereof.

Figure 1 is a perspective view of a horseshoe-calk, showing my design. Fig. 2 is a side elevation of the same. Fig. 3 is a bottom plan view of the calk.

The leading feature of my design consists in a square collar having at each corner a wing the outer edge of which is converging toward the outer edge of each other wing and constituting an inverted truncated pyramid

having a flat lower end and grooves tapering 20 in width and depth, being narrower at the small end between said wings.

In said drawings, A is the square collar, having the shank B, on which is cut a screw-thread slightly tapering toward its outer end, 25 and under said collar are the tapering wings C, constituting the truncated pyramid, having the tapering grooves D between said wings.

Having thus described my invention, what I claim is—

The design for a horseshoe-calk substantially as herein shown and described.

In testimony whereof I affix my signature in presence of two witnesses.

RICHARD WHITAKER.
